(57) **CLAIM**

The ornamental design for a watch case, as shown and described.

DESCRIPTION

FIG. 1 is a front view of the watch case.

FIG. 2 is a rear view of the watch case.

FIG. 3 is a right side view of the watch case.

FIG. 4 is a left side view of the watch case.

FIG. 5 is a bottom view of the watch case.

FIG. 6 is a top view of the watch case; and,

FIG. 7 is a perspective view of the watch case.

The broken lines in the drawings are used to show portions of the watch case that do not form part of the claimed design.
